WRENCH HAVING SEPARABLE WORK EN-
CIRCLING PORTION AND PIVOTED DOG
GRIPPERS

G. Eugene Werner, Portland, Oreg.

Application September 12, 1945, Serial No. 615,781

5 Claims. (Cl. 81—111)

1

This invention relates to a pipe wrench. More particularly it relates to a close quarters pipe wrench which is equally useful where there is an abundance of room.

An object of the invention is to produce a pipe wrench that will screw or unscrew a pipe, either in repair work or new installations where the space around the pipe for a wrench to work is very restricted.

Another object is to provide a pipe wrench, the operating head of which is divisible into parts for encompassing or removal from a pipe, so that even with pipes that lie against a wall, the pipe wrench may be applied and used by springing the pipe a fractional part of an inch away.

A further object is to produce a pipe wrench structure employing the usual toothed pipe grabbing parts in plural arrangement within the wrench head, but with each of such parts working independently of all others so that a flat or hard spot, sometimes encountered, will not interfere with the operation of the wrench.

The foregoing and other objects that will be plain to makers and users of pipe tools, constitute the purpose of this invention, the particular advantageous features of which are pointed out clearly in the claims that complete this specification.

A drawing exemplifying the best form in which I contemplate making this wrench is shown for purposes of explanation but not as defining the scope of the invention.

In the drawing:

Fig. 1 is a side view of a complete wrench according to the invention with parts sectioned for clarity of disclosure;

Fig. 2 is a perspective view of one of the parts of the wrench head, that mates with its counterpart to complete a head as shown in Fig. 1;

Fig. 3 is a partly sectioned view of Fig. 1 taken on the line 3—3 of Fig. 1; and

Fig. 4 is a cross section of Fig. 1 on the line 4—4.

Further describing the structure shown in the drawing. An annular ring-like wrench head indicated by numeral 1 with a tang portion T is made of two duplicate parts, one of which is indicated by numeral 1 in Fig. 2. The joint between the parts is made intercepting as at 2 and the one shown can be regarded as the lower one in Fig. 1. The peculiar intercepting joint having the necessary resistance to stress in any direction, when complete, is formed by placing both a tongue and an adjacent groove on each piece, the surfaces being exact duplicates, which

interlock when one part is reversed for lateral engagement as shown in Fig. 3. These parts or halves of the head are provided with pockets 3 within which are swingably mounted toothed pipe dogs 4, said pockets being provided with cylindrical seats to which the dogs 4 are smoothly fitted; the cylindrical portion of the pockets 3 and the dogs being in each case a bit more than a semi-cylinder so that the dogs being inserted endwise will not fall out. Each dog is made with a toothed pipe engaging part 5, which is backed by a spring 7. The two parts, after being brought together as shown in Fig. 1, are securely locked into working position by the socket handle 8, which engages by a system of interrupted threads 9 inside of the socket handle 8, which mate with a complementary interrupted thread system 10 on the two parts of the tang T.

A pipe in position to be worked is indicated 20 by numeral 11 in Fig. 1, and as shown in that figure, working the handle 8 up and down will impart an intermittent counter-clockwise revolving motion to the pipe 11, screwing or unscrewing it according to which end is threaded into 25 a fitting, the pipe serving as a ratchet wheel and the dogs as pawls. Should reverse motion be required, the tool can be taken off and reassembled the opposite side up. As drawn, there is a dog in each half of the head, each of which applies its turning force to the pipe independently 30 of the other, by virtue of the arcuate pipe supports 12 which will be an easy running fit for a given size of pipe.

At the same time that the threaded socket is holding the tang T firmly in position with respect to its two parts, the intercepting joint is holding the other side of the head and if the tool is made of proper material, alloy steels are suggested, the result is a wrench that is light, 40 small enough to engage and turn a pipe in almost any position it may be found and also strong enough to take any manual force that can be applied to it. It is intended that a set of wrenches comprising a head for each size of pipe and a handle that takes any of the heads, for sizes say up to and including 1½" pipe can successfully be made with two pipe dogs as shown, while larger sizes can be made with two dogs in each part of the head and a larger tang and handle.

Having fully disclosed my pipe wrench so that anyone familiar with such tools can understand its manufacture and use, what I claim as new and desire to secure by Letters Patent, is:

1. A wrench for pipes and the like comprising a two part annular ring-like head member

each part having an integral threaded half tang for a handle, the said parts made intercepting for interlocking together by duplicate longitudinal tongues and adjacent grooves in the two part head, said tongues and grooves being parallel to the longitudinal axis of said head, said interlocking completed by reversing a ring part and matching the tongues into the grooves, a socketed handle member, screw fitted to the tang, the head member being provided with cylindrical dog seats and dogs in said seats that project within the inside of the ring-like head member to engage a pipe encompassed by the head.

2. A close quarters wrench for pipes and the like cylindrical bodies comprising an annular ring member, the inside diameter of which is a running fit for the cylindrical body, said ring being in two equal half parts, a semicylindrical tang integral with each part, longitudinal tongue and groove intercepting means formed on the ring, said intercepting means being duplicate tongue and adjacent groove means on each piece, that will interengage when one part is reversed with respect to the other, so that the two half parts form a ring, a socketed handle made to fit over the tangs when brought together and lockable therewith by a part revolution of said handle, the said ring having pipe engaging jaws on the inside thereof and the two ring parts with tangs movable towards each other from free to locking engagement after the same are placed around a pipe.

3. A wrench for pipes or the like comprising an annular ring-like head portion comprising two separable half parts each provided with an integral threaded half tang, the two parts of said head being duplicates, interlockingly engageable by a tongue with adjacent groove on each part, said tongues and grooves being parallel with the plane of separation of the ring, an interiorly threaded socket-like handle effective to complete the interlocking of the said halves, when it is threadably engaged with the threaded tang, and engaging means mounted within

said head portion for taking hold of a round object such as pipe.

4. A close quarters wrench for pipes or the like comprising a pair of duplicate half head portions, each portion having an integral half tang thereon, a socketed handle adapted to rigidly engage the tang parts when aligned together, pipe engaging means within at least one part of the ring and means for locking the sides of the ring farthest from the tang, comprising duplicate groove and tongue means immediately adjacent, on each piece, each groove and tongue being parallel to the longitudinal axis of the half head portions and being of angular section.

5. A close quarters wrench, comprising a two part separable head defined as duplicate half annular ring portions each with an integral half tang portion projecting therefrom, said parts movable sidewise together to lock into an annular ring with a tang, said tang parts and the opposite parting surfaces of the ring each being provided with a groove and a mating tongue, said grooves and tongues parallel to the longitudinal axis of the head parts and so formed that when moved sidewise together the grooves and tongues interlock against any separating movement save the reverse of the movement that brought them together, pipe engaging means carried by the ring formed of the parts and a handle fitted on the complete tang.
